MEASURING VALVE

Howard C. Allen, Vancouver, British Columbia,
Canada

Application October 29, 1934, Serial No. 750,585

5 Claims. (Cl. 225—9)

My invention relates to improvements in measuring valves which are particularly adapted for dispensing effervescent beverages, such as mineral waters, beer and the like.

5 The objects of the invention are to provide means whereby the measuring vessel is closed by the admission of a predetermined quantity of liquid and is held closed by the pressure within the supply pipe; to provide means whereby only 10 a momentary movement of the operating lever either to filling or discharging position is necessary to cause the valve to fill or discharge as the case may be.

The invention consists essentially of a measuring chamber having a valve associated therewith, said valve having two ports one to admit a portion of liquid from a source of supply to the chamber and another to discharge all the liquid therefrom, and a further valve adapted for 20 opening in response to the movement of the first valve for admitting further liquid to the chamber, as will be more fully described in the following specification and shown in the accompanying drawing, in which:—

25 Fig. 1 is a sectional plan view of the invention with the main valve in neutral position taken on the line 1—1 of Figure 2.

Fig. 2 is a vertical sectional view taken on the line 2—2 of Fig. 1.

30 Fig. 3 is a vertical sectional view taken on the line 3—3 of Figure 1.

Fig. 4 is a fragmentary plan view showing the main valve turned to filling position.

35 Fig. 5 is a fragmentary plan view showing the main valve turned to discharge position.

In the drawing like characters of reference indicate corresponding parts in each figure.

The numeral 1 indicates a base having an inlet connection 2 provided with a passage 3, leading 40 to a valve barrel 4. The base is also provided with an outlet passage 5 leading from the valve barrel 4 to a discharge spout 6 and an outlet passage 7 leading from the upper wall of the base to the valve barrel.

45 An inverted valve seat 8 is provided in a port 9 which communicates between the upper wall of the base and the passage 3.

Above the base 1 is a chamber 10 which is preferably enclosed by a cylindrical wall 11 of glass and is covered by a head 12. The head is recessed on its upper side as at 13 and is fitted with two valves respectively numbered 14 and 15. The valve 14 is fitted with a float 16 which is adapted to be raised by liquid entering the chamber or measuring vessel 10 to close the valve. The valve

15 is spring loaded to hold it normally closed and is provided with a stem 17 by which it is opened, this valve communicates between the recess 13 and the chamber 10 to allow air to enter said chamber when the liquid in the chamber is being 5 discharged.

Slidably mounted between the base 1 and the head 12 is a stem 18 supporting a valve 19 which is adapted to close against the seat and be held against opening by the pressure of supply liquid 10 below it. The stem 18 is adjustably fitted with a float 20 for the purpose of closing the valve 19 when a suitable quantity of liquid has entered the chamber 10.

Fitted in the valve barrel 4 is a valve plug 21 15 having angular passages or ports 22 and 23 which are at different levels. The port 22 is adapted to register with the passage 3 and a further passage 24 which communicates with the chamber 10, and the port 23 is adapted to register with the passages 5 and 7. The valve plug is provided with a stem 25 which extends through a gland 26 in the head 12 and through a cover 27 therefor, and is fitted at its upper extremity with a lever handle 28 adapted to rest when in 25 normal position parallel to and directly above the discharge spout 6. Fitted upon the stem and within the recess 13 is a lever 29, which when the handle 28 is turned to the right to discharge the contents of the chamber 10, will bear upon 30 the stem 17 of the valve 15 to open it.

Preferably in the inverted seat of the float 14 is a seat 30 which is covered by a ball or other closure 31, thus forming a relief valve 32 which will close at a predetermined pressure and prevent air from entering the chamber when in use.

In operating the valve to fill it, the handle 28 is swung to the left from normal position, until the port 22 of the valve plug 21 registers with the passages 3 and 24 when liquid will flow into 40 the chamber 10, thus momentarily reducing the pressure beneath the valve 19 and permitting it to drop to open position. The handle is then swung back to normal position, closing off the flow through the valve plug, filling then takes 45 place solely through the valve seat 8, and as the liquid rises in the chamber to a predetermined level the float 20 rises and closes the valve 19 against its seat 8. If through inattention on the part of the operator, the handle is held to 50 the left of normal position, liquid will continue to flow into the chamber until the float 16 rises and closes the valve 14.

To discharge the valve, the lever is swung to the right, thus disposing the port 23 to register 55

with the passages 7 and 5 and simultaneously causing the arm 29 to bear against the stem 11 of the valve 15 to open it and allow air to enter the chamber as the liquid passes outwards therefrom through the spout 6.

5. What I claim as my invention is:

1. A measuring valve comprising a chamber having a base and side walls, said base having an inlet connection and a discharge outlet, a float valve for admitting liquid to a predetermined level in the chamber from the inlet connection, a bye-pass valve from the inlet connection to the chamber adapted when open to relieve the pressure of the liquid supply and open the float valve, and a valve for discharging the liquid from the chamber through the outlet.

10. 2. A measuring valve as claimed in claim 1, said bye-pass valve and the valve for discharging the liquid from the chamber being incorporated in a single unit.

15. 3. A measuring valve comprising a chamber having a base, side walls and a head, said base having an inlet connection and an inlet passage leading therefrom to the chamber, a discharge outlet through said base, a manually operable valve within the base normally closing the in-

let passage and the discharge from the chamber, said valve in one position establishing communication through the inlet passage to the chamber and in another position establishing communication through the discharge, and a further valve communicating with the inlet passage and the chamber adapted to open by gravity subsequent to the initial movement of the manual valve to admit liquid to the chamber.

20. 4. A measuring valve having a base, side walls 10 and a head, said base having separate passages for liquid inlet to the chamber and for discharge therefrom, a manually operable valve for selectively opening each passage, a float valve communicating with the liquid inlet passage adapted 15 to close when a predetermined liquid level is reached in the chamber and to be held closed on discharging the liquid from the chamber by pressure in the inlet passage, and a second float valve for sealing the chamber against incoming 20 liquid.

25. 5. A measuring valve as claimed in claim 4, said second float valve being disposed to close the egress of air from the chamber during the filling operation.

HOWARD C. ALLEN.
